HEIGHT GAUGE PEDESTAL

Otto Wiegel, Chicago, Ill. (½ Industrial Tool Works,
3541 Martens St., Franklin Park, Ill.)

Filed June 26, 1961, Ser. No. 65,740

Term of patent 14 years

(Cl. D52—6)

FIG. 1 is a perspective view of a height gauge pedestal on a reduced scale, showing my new design;

FIG. 2 is an elevational view, showing one face of the pedestal with the broken line elements omitted for convenience of illustration.

FIG. 3 is a horizontal sectional view, taken substantially along the line 3—3 of FIG. 2.

The three faces of the pedestal not shown in FIG. 2, are substantially the same as that shown.

The essential features of the design reside in the solid line portions.

I claim:

The ornamental design for a height gauge pedestal, substantially as shown and described.
